UNITED STATES PATENT OFFICE.

ALFRED W. DUNN, OF ROCHESTER, NEW YORK, ASSIGNOR TO WILLIAM EASTWOOD & SON COMPANY, OF ROCHESTER, NEW YORK, A CORPORATION OF NEW YORK.

SHOE-FORMING MACHINE.

1,019,310.

Specification of Letters Patent.

Patented Mar. 5, 1912.

Application filed April 26, 1909. Serial No. 492,105.

To all whom it may concern:

Be it known that I, ALFRED W. DUNN, of Rochester, in the county of Monroe and State of New York, have invented certain new and useful Improvements in Shoe-Forming Machines; and I do hereby declare the following to be a full, clear, and exact description of the same, reference being had to the accompanying drawings, forming a part of the specification, and to the reference-numerals marked thereon.

The present invention relates to the manufacture of shoes and it has for an object to provide a machine for uniting uppers of shoes to soles in such a manner that it is possible to dispense with the tacking of the uppers to lasts and with several operations requiring the handling of the upper on the last.

20 Another object of the invention is to provide a machine for shaping shoe uppers on lasts in an expeditious manner.

To these and other ends the invention consists in certain improvements and combinations of parts all as will be hereinafter more fully described, the novel features being pointed out in the claims at the end of the specification.

In the drawings: Figure 1 is a vertical section of a machine constructed in accordance with the present invention and showing a sandal in section after the sole and the upper have been united. Fig. 2 is an end view of the same machine. Fig. 3 is a plan view partially broken away. Fig. 4 is a detail sectional view illustrating the method of applying the shoe parts to the machine; Fig. 5 is a detail sectional view showing the manner in which the vamp is stretched over the form or last. Fig. 6 is a detail view showing the manner in which the back part of the upper is presented to the form or last, and Fig. 7 is a perspective view of a sandal after the latter has been removed from the machine, the last being shown in position therein.

In the manufacture of shoes, such as sandals, in which the uppers have outwardly turned flanges united to the soles, a great number of operations has been necessary and these operations have required that the uppers be tacked or otherwise fastened during the shaping, thus producing holes which disfigure the shoe and destroy its efficiency.

55 Further, the stretching of the upper has

heretofore varied, that is, the leather has been stretched more in some shoes than in others. In this invention an upper is united to a sole by the same operation which shapes it, thus rendering it unnecessary to employ tacks to hold the upper while the sole is being applied.

The invention in the present instance will be described in connection with the manufacture of sandals, such as shown in Fig. 7, in which the upper is composed of a vamp 1 and a separate back piece 2, the latter overlapping the former at 3 and both having outwardly turned flanges 4 at their lower edges united to the sole 5. In making the sandal vamp 1, the back piece 2 and the sole 3 are cut in the forms shown and the back piece has a buckle or other fastening device 6 secured thereto for engagement with a strap 7 which, when the sandal is completed, is passed through slits in a tongue 8 on the vamp.

In carrying out the present invention, the sole 5 is laid upon a sole support 10 that may be detachably supported in a receptacle 11 on main frame 12 and have a depression 13 in its upper surface shaped to receive the sole 5, the support being made detachable in order that other supports for shoes of different sizes may be employed. It is also preferred to coat the edge of the sole with an adhesive 14, such as a rubber cement, in order that the upper may be secured thereto during the shaping. A last or other form 15 bearing a known relation in size to the sole and having its external surface corresponding to the desired shape of the upper, is then placed upon the sole and the upper is then shaped on the last by a shaping mechanism comprising preferably a vamp die 16 and a back piece die 17, the former having an internal wall corresponding in shape to the external vamp portion of the last 15, while the latter has a wall corresponding in shape to the external heel or back portion of the last. The vamp and the back piece die may be located at opposite sides of the sole support and movable toward and from each other on the shaping operation, this movement being preferably effected by pivoting the dies at 18 on opposite sides of the receptacle 11 and providing them with a common operating means so that the dies move simultaneously toward the last and coöperate with the same simul-

taneously, thus causing the last to be properly positioned or centered on the sole.

The common operating means for the dies may comprise a lever 19 pivoted at 20 to the frame of the machine and connected by a link 21 with a slide 22 which carries a cross head 23, the opposite ends of the cross head being connected to the dies by links 24, arranged in pairs at each end and having each member of the pair connected to a die. A depression of the treadle or operating lever 19 will move the dies toward the last and will expand coil spring 25 that is secured to the cross head 23 and to the main frame so that when the treadle is released after the shaping operation the spring elevates the dies.

In carrying out this method, after last 15 has been placed upon sole 5, the vamp blank 1, which previously has been coated with an adhesive along its lower and its overlapped portion 3 and then moistened, is laid loosely in proper position on the last or form, while the back piece blank also coated with an adhesive along its lower edge and overlapping portion 3 and then moistened, is fitted within die 17, in the manner shown in Fig. 5, with its strap 7 held by the buckle 6. The lower forward edges of the back piece, 30 are now turned outwardly by hand and held in this position while the dies are being moved toward the last. In moving toward the last, the edge 27 on the vamp die first frictionally but loosely engages the vamp blank in an unbroken line about the last and away from the lower edge of the blank, thus causing a slight stretching of the vamp over the last, the stretching being immediately followed by a clamping or pressing of the 40 lower edge of the vamp against the sole by the outwardly presented flange 28. During the stretching of the vamp, the back piece 2 is applied to the last and shaped, thus causing the forward ends of the back piece to overlap the rear ends of the vamp and its edge to be pressed against the sole by the outwardly presented flange 29 simultaneously with the pressing of the edge of the vamp against the sole. After a sufficient 50 pressure on the outwardly turned portion of the upper has been applied the dies may be raised and the shoe with the last therein removed from the machine for stitching and other operations. For making shoes of 55 other sizes other dies and sole supports are substituted for those herein shown, the sole support 10 merely resting in the receptacle 11 so that it may be quickly removed and the dies being detached by removing bolts 60 or pivots 18 and the pivots 30 that connect the operating means to the dies. If it is desired only to shape the upper, the sole may be replaced by another similarly shaped surface which will project beyond the edges 65 of the last so that the lower edge of the

upper may be deflected outwardly to be pressed by the portions 28 and 29.

With this invention it is possible to manufacture shoes at a great deal less expense, as the operation of nailing the upper while it is being shaped is dispensed with and the shaping of the upper and the uniting of the sole thereto is accomplished by one operation, whereas fully four have been necessary heretofore. Further the disfiguration of the upper by driving tacks therein is entirely overcome.

I claim as my invention:

1. In a shoe machine, the combination with a sole support, of upper shaping mechanism of two parts swinging toward and from each other and into and out of cooperation with a last supported on a sole on the support to shape the upper and having lateral portions adapted to engage the edges 85 of the upper to press said edges flatwise into engagement with the sole.

2. In a shoe machine, the combination with a sole support, of vamp and back piece shaping dies operating toward and from a last supported on a sole on the support, and common operating means for said dies.

3. In a shoe machine, the combination with a support having a depression therein formed to receive a sole, of upper shaping 95 mechanism coöperating with a last supported on a sole in the depression to shape an upper over the last and having lateral portions adapted to engage the edges of the upper to press said edges flatwise into engagement with the sole in the depression.

4. In a shoe machine, the combination with a support for a shoe sole, of a pair of upper shaping die members movable toward and from the toe and the heel of a last arranged on a sole on the support to press the edges of the upper against the sole.

5. In a shoe machine, the combination with a support for a sole, of a pair of pivotally mounted upper shaping dies movable 11 toward and from the toe and the heel of a last arranged on a sole on the sole support.

6. In a shoe machine, the combination with a sole support, of pivotally mounted vamp and back piece dies operating toward 11 and from each other at opposite sides of the support, and a common operating means for said dies.

7. In a shoe machine, the combination with a sole support, of pivotally mounted 12 vamp and back piece dies operating toward and from each other at opposite sides of the support, and a common operating means for said dies embodying a treadle, a cross head and two pairs of links, each pair connecting 12 one end of the cross head to one side of each die.

8. In a shoe machine, the combination with a support and a relatively stationary form having a portion shaped to correspond 130

to the vamp of an upper, of a die member pivotally mounted on the support to one side of the form and having an internal wall corresponding to the exterior wall of the form, and movable into coöperative relation therewith in a downward direction toward the sole of the form.

9. In a shoe machine, the combination with a support and a relatively stationary form having a portion shaped externally to correspond to the back of an upper, of a die member having an interior wall corresponding to the external wall of the form, said members being movable on the support into and out of operative relation to the form in a downward and longitudinal direction relatively to the latter.

10. In a shoe machine, the combination

with a support and a relatively stationary form having a portion shaped externally to correspond to the back of an upper, of a die having an interior shape corresponding to the external shape of the form and pivoted to the support beyond one end of the form to move in the plane of the longitudinal extent of the latter.

11. The combination with a suitably supported last, of a pair of die members movable toward and from the last from opposite sides thereof, and means for simultaneously moving said die members toward the last.

ALFRED W. DUNN.
